(57) **CLAIM**

We claim the ornamental design for laptop computer, as shown and described.

DESCRIPTION

FIG. 1 is a front perspective view of the laptop computer comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof; and

FIG. 9 is a front perspective view of the laptop computer in an open position; and,

FIG. 10 is a detailed view as indicated in FIG. 9.

Broken lines shown in the drawings illustrate portions of the laptop computer that form no part of the claimed design.

1 Claim, 8 Drawing Sheets
